C. S. BUSHNELL

AUTOMATIC TRAIN CONTROL TRACK ELEMENT

Filed Dec. 7, 1921

FIG. 1.

FIG. 2.

FIG. 3.

C. S. Bushnell,
INVENTOR.
BY Neil H. Preston,
his ATTORNEY.

UNITED STATES PATENT OFFICE.

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL TRACK ELEMENT.

Application filed December 7, 1921. Serial No. 520,683.

To all whom it may concern:

Be it known that I, CHARLES S. BUSHNELL, a citizen of the United States of America, residing at Rochester, in the county of Monroe and State of New York, have invented certain new and useful Improvements in Automatic Train-Control Track Elements, of which the following is a specification.

This invention relates to a mounting or structure for supporting, enclosing and protecting track influence elements or devices employed in train control systems.

In automatic train control and cab signaling systems, it is necessary to communicate control influences from the trackway to the moving trains at the proper time and thereby set into operation suitable apparatus on the train which may bring the train to a stop or impose some other form of automatic control. In systems of this kind it is believed expedient to communicate such influences by magnetic or electro-magnetic induction, rather than by physical contact between devices along the track and cooperating devices on the moving train. In certain types of such inductive systems insulated coils, suitably associated with the partial magnetic circuit of the track element are controlled by suitable devices, such as relays of track circuits, and the like, whereby the controlling condition of the track element may be changed to correspond to the conditions of the track. Such track elements are continually exposed to the weather, subjected to severe jar and vibration due to moving trains, and are liable to be hit by the dragging equipment of passing trains; and in order that such track elements may give reliable service, which is one of the essentials of any useful train control or signaling system, it is important to properly mount and house them.

With these and other considerations in mind, one of the principal objects of the present invention is to provide a structure for supporting and enclosing track elements of the type mentioned, which, while cheap and easily installed or replaced, will protect the coils and core of the element from weather, dragging equipment and other injurious agencies, and will at the same time

allow the element to perform its proper function.

Other objects and advantages of the invention will appear as the description progresses.

In describing the invention in detail, reference will be made to the accompanying drawings, in which:

Fig. 1 is a plan view of a track element and its mounting, part of the mouldable material being omitted for clearness;

Fig. 2 is a side elevation of the device shown in Fig. 1; and

Fig. 3 is a sectional elevation taken on the line 3—3 in Fig. 1.

In the particular embodiment of the present invention illustrated, the track element T consists of a core 1 of a general U-shape which may be constructed of steel and be permanently magnetized, or which may be constructed of soft iron which will not hold its magnetism. If a soft iron core is used, it is preferably made of laminated material whereby the effect of eddy currents is reduced, thus making it more quickly responsive to a change of magnetic flux density when the magneto-motive-force or reluctance is varied. The upstanding ends of the U-shaped core are provided with coils 2 which are wound and connected in series and in a manner act together in producing or opposing the passage of flux through the core 1. These coils 2 may be connected in an energized circuit or not, which current may be normally open or normally closed, depending on what particular kind of car equipment is used in connection therewith, in each case the opening or closing of the circuit changing the condition of the track element to transmit the desired control influence to the moving vehicle. To each end of the core 1 is fastened by screws, rivets, or the like, a pole piece 4 of suitable thickness, solid or laminated, and preferably of rectangular shape and considerably larger than the face of the core whereby the area of the flux emitting face is considerably increased.

No matter what specific form of the track element is used, whether the core thereof is permanently magnetized or not, in each case

the core comprises a partial magnetic circuit which should not be disturbed or bridged by magnetic material; and consequently any housing or mounting for such 5 track element should be constructed of non-magnetic material. Also, the track element should be firmly secured in place and supported so as to be maintained in a definite relation to the track rails; and for this 10 reason it is preferred to make the frame or casing 5 of a suitable non-magnetic metal, preferably a manganese steel casting. For ordinary service it is considered best to support the track element directly on top of 15 the ties, either between the track rails, or on the outside thereof, depending on the type of system and the disposition of the cooperating car equipment. When the track element is to be supported between track 20 rails, as shown the frame or casing 5 is made shallow so as not to project so high as to be struck by any fixed parts of the rolling stock, the upper face of the track element being ordinarily on a level with, or 25 slightly below, the treads of the track rails.

The casing or frame 5 is formed with a central opening to receive the core 1 and its coils 2, and on account of the size of the coils and the elongated pole pieces 4 this 30 opening is of a general I-shape in the particular construction shown. This opening is surrounded by a flange or web to strengthen and stiffen the frame 5. While this opening may be closed at the bottom with an integral 35 wall or separate plate of suitable material, which does not have to be non-magnetic, for ordinary uses the frame rests directly against the top of a tie.

The ends of the frame 5 are sloped or 40 ramped downward, as shown in Fig. 2, and also have their edges converging. The upper surface of these ends may be flat or rounded, or otherwise suitably shaped to form approaches that will lift up or deflect 45 sidewise any dragging brake equipment and thereby prevent the track element and its mounting from being torn up or injured by such dragging equipment.

These sloping ends are hollow and provided with a re-enforcing rib 6, thereby 50 economizing in the amount of material necessary and also affording pockets through which wires may be led from the I-shaped opening into a conduit 7 extending under 55 the sloped ends of the frame 5. This structure or frame 5 is provided with lugs for supporting the same on three ties by suitable spikes or lag screws 8, thus facilitating the maintenance of the track, since the ties may 60 be replaced one at a time without disturbing the position of the track element.

The coils 2 are preferably impregnated with a suitable insulating compound by the usual vacuum process of impregnation, are 65 taped or otherwise suitably covered, and are

further preferably coated with a thick layer of some suitable compound having insulating and moisture resisting properties, and also possessing a consistency such that it will not soften or flow at the ordinary temperature to which the track element is subjected. The lamina of the core 1 and the pole pieces 4 may be painted, or otherwise suitably treated, so as to resist the injurious effects of moisture and gases. A track element is set in the opening in the frame 5. The lead-in wires 9 and 10 are brought through holes extending from the I-shaped opening under the approaches or sloped ends of the frame 5, so that they may be connected through the conduit 7 to suitable circuit controlling devices controlled in any suitable manner. With the track element T in this position plastic material 11, comprising a composition of sulphur, graphite and stones, or concrete or the like, is poured in the frame 5 and moulded around the track element, thus firmly holding it in place and protecting it from the weather and other harmful agencies. 70 80 85 90

The mounting or housing for the track elements is cheap, rugged, durable and of a construction that is easily installed. The sloping and converging approaches tend to lift or divert any object that is apt to strike it, such as dragging braking equipment of a moving train, or the like. It should also be noted that while the coils and core of the track element are efficiently housed and protected by a casing having the necessary strength and rigidity, this casing does not detract from the magnetic properties of the track element and does not prevent it from performing a desired function of transmitting flux in a definite path or loop through the coils. The desired fixed relation between the track element itself and its protecting case is established and maintained by a plastic material which takes care of slight variations in the size of the parts. This plastic and mouldable fastening is obviously far superior to any mechanical fastening, such as bolts, pins and the like, which, among other things, are quite likely to loosen or even break under the severe 100 105 110 115 shocks and vibration to which the device is subjected by the passing of trains.

The particular shape of the manganese steel casting, the size and disposition of the core and its coils, and various other detailed features of the specific construction illustrated are susceptible to considerable adaptations and modifications in practice, depending on the particular type of system and practical working conditions. Such 120 125 modifications will be evident to those skilled in this art without detailed illustration and description.

Having thus illustrated and described one specific form of my invention, I desire 130

to have it understood that the present embodiment illustrated is subject to various modifications and adaptations, without departing from the spirit or scope underlying

5 the present invention.

What I desire to secure by Letters Patent, is:

1. A track device for cooperating with a car-carried device to convey a controlling influence from the trackway to the moving vehicle in a train control system comprising, a non-magnetic casing, a track element in said casing coated with a thick layer of insulating compound, and plastic material moulded between said casing and element to firmly hold the element in position. 10
2. A mounting for supporting track elements of inductive train control systems comprising, a box-like structure of non-magnetic material having downwardly sloping and converging hollow approaches, and means for bringing control wires through the side of said structure under said approaches. 20
3. A box-like structure for mounting track elements of train control systems comprising, a frame of non-magnetic material having a large opening therethrough, a railway tie under said opening to form a bottom for said structure, inclined approaches for said structure, and means for leading wires from said structure under said inclined approaches. 25
4. A structure for supporting track elements of train control systems comprising, a frame having a large opening of general I-shape extending therethrough, said frame having sloping and converging approaches on opposite sides of said opening. 35
5. A track element and mounting for inductive influence communicating means for train control systems comprising, a magnetic core of general U-shape having a coil thereon, insulating compound surrounding said core and coil, a non-magnetic casing, and mouldable material surrounding said element for holding it in vertical spaced relation with said casing. 40
6. A structure for supporting track elements of train control systems comprising, a frame having sloping approaches and constructed of non-magnetic material, and lugs on said structure for receiving anchoring means spaced substantially the distance of adjacent railway ties of the usual construction. 50
7. A track element and mounting for train control systems of the inductive type comprising, a casing of non-magnetic material, a track element in said casing consisting of a core of soft iron having a coil thereon, insulation surrounding said coil, and concrete moulded between said casing and element to firmly hold the element in position in said casing. 55

8. A mounting for track elements of inductive train control systems comprising, a casing of non-magnetic metal having converging ramped ends. 70

9. A mounting for track elements of inductive train control systems comprising, a frame of non-magnetic metal having a central opening to receive a track element, and a tie below said opening to form a box-like mounting. 75

10. A mounting for track elements of inductive train control systems comprising, a shallow frame of non-magnetic metal fastened to the top of the ties, sloping hollow approaches built integral with said frame, each of said approaches being provided with a reinforcing rib on the underside thereof. 80

11. A mounting for track elements of inductive train control systems comprising, a casing of manganese steel having ramped ends and a central opening to receive a track element. 85

12. In a track device for communicating controlling influences from the trackway to moving trains, the combination with a non-magnetic metallic casing, a track element in said casing including a magnetic core and coils, and plastic material filling the space between said track element and casing. 90

13. In a track device for communicating controlling influences from the trackway to communicating trains, the combination with a non-magnetic metallic casing, a track element in said casing and having coils thereon impregnated with an insulating compound, 100 and concrete moulded between the casing and track element.

14. A trackway device for inductively communicating controlling influences to a suitable car-carried influence receiving device when such receiving device passes by such trackway device comprising, a U-shaped core of laminated magnetic material, a coil on said core, pole pieces of magnetic material secured to the ends of said core, 105 and a housing of non-magnetic material inclosing said core and coil in a manner so that the top face of said pole pieces are flush with the upper surface of the top of said housing. 115

15. A trackway structure for intermittent inductive train control systems comprising, the usual pair of spaced track rails, a U-shaped laminated core terminating in enlarged pole pieces flush with the top of said rails and disposed crosswise of said rails, a coil on said core, a housing of non-magnetic material for inclosing said core and coil to protect the same against the detrimental effects of moisture, and ramped approaches 120 leading to and from said housing in a direction parallel to the track rails. 125

16. A casing for mounting track elements for train control systems of the inductive type comprising, a box-like structure having 130

two pairs of oppositely disposed walls, sloping ramped approaches disposed adjacent to one pair of said walls, re-enforcing ribs near the edges of the approaches and extending downwardly therefrom to form inverted pockets, one of said last mentioned walls being provided with an opening to permit lead-in wires to run from said box-like structure into one of said pockets.

10 17. An influence communicating device for automatic train control systems comprising, a non-magnetic casing, a U-shaped

core of magnetic material terminating in enlarged pole pieces supported in an upright position in said casing, so that the top faces of said pole pieces are flush with the upper surface of the top of said casing, a coil on said core, and means including said casing for protecting said coil against exposure to the atmosphere.

15 20 In testimony whereof I hereto affix my signature.

CHARLES S. BUSHNELL.
